 Decarie Incinerator Corporation, New York,
 N. Y., a corporation of New York

Application December 24, 1934, Serial No. 758,911

1 Claim. (Cl. 202—104)

My invention relates to improvements in the burning or roasting of solids containing vaporizable, combustible material such as oil saturated mineral absorbents. My invention is of special 5 value and application in connection with the burning of such mineral absorbents to recover them for reuse.

Burning operations to recover oil saturated mineral absorbents, such as fuller's earth, clays 10 and like materials, to recover them for reuse, are commonly carried out in tiered multiple hearth furnaces provided with rotary rabbles driven from a common shaft extending vertically through the several hearths, the oil saturated absorbent being 15 supplied to the uppermost hearth, the oil content of the absorbent being utilized as fuel for the operation, and the burned product being discharged from the lowermost hearth.

In Letters Patent No. 1,943,976, granted January 16, 1934 on my application, I have described 20 an improved method of conducting such burning operations to recover oil saturated mineral absorbents, which, as practiced in such tiered multiple hearth furnaces, involves in effect the separation 25 of the furnace into two parts, an upper part in which absorbed oil is vaporized from the absorbent without substantial combustion of this oil and a lower part in which the burning of the absorbent may be completed in much the usual manner. My present invention provides an improved 30 apparatus for carrying out operations of this general character involving further the complete elimination of combustion from that region in the furnace within which separation of absorbed oil by vaporization from the absorbent 35 without combustion of such oil is effected.

The improved apparatus of my invention, embodied in a tiered multiple hearth furnace of otherwise conventional construction, comprising 40 a series of superimposed hearths and a corresponding series of rabble arms, having rotary rabbles, rabble teeth or a combination of both, driven from a common vertical shaft for moving solids over the several hearths and generally 45 downwardly through the furnace, comprises means for isolating the atmosphere of the hearths in the upper part of the furnace from that of the hearths in the lower part, combustion chambers arranged beneath the hearths in the upper 50 part of the furnace with means for isolating the atmosphere in these combustion chambers from that over the hearths in the upper part of the furnace, and means for indirectly transferring heat from the combustion chambers to solids 55 moving over these hearths in the upper part of

the furnace, and means for conveying solids downwardly from hearth to hearth in the upper part of the furnace through these combustion chambers but out of contact with the atmosphere in these combustion chambers. My invention 5 thus provides compact, efficient and economically constructed and operated apparatus for maintaining optimum processing conditions.

In the apparatus of my invention, the means 10 for conveying solids through these combustion chambers but out of contact with the atmosphere therein, from hearth to hearth in the upper part of the furnace, are provided in the form of tubes closed with respect to the combustion chambers and extending therethrough connecting apertures 15 in each hearth with aligned apertures in the roof of the next lower hearth. To facilitate the transfer of heat from the combustion chambers to the solids moving over the hearths in the upper part 20 of the furnace, these tubes are with advantage made of material of high thermal conductivity, carborundum, iron chrome alloys, cast iron, and the like. These tubes may be baffled to increase 25 the heat transfer. Inserts of similar material may also be arranged in the roofs, and in the floors as well, of the combustion chambers to the same end. Heat transfer to solids moving through such tubes is, however, particularly effective. Repairs are facilitated by making such 30 tubes removable.

My invention will be further described in connection with the accompanying drawings, which 35 illustrate the apparatus of my invention. It is intended, and will be understood, that this further and more detailed description of particular embodiments of my invention is intended by way of exemplification only and that my invention is not limited to the specific apparatus illustrated. In the accompanying drawings:

Fig. 1 is a fragmentary elevation in section, 40 with parts broken away, of a furnace embodying my invention;

Fig. 2 is a section on line 2—2 of Fig. 1;

Fig. 3 is a section on line 3—3 of Fig. 1, showing the details of the construction of drop tubes embodied in this furnace; and

Fig. 4 is a section showing a modified construction of drop tubes.

In the furnace illustrated 1 represents a chute through which the oil saturated mineral absorbent is supplied to the uppermost hearth 2 by means of a conventional screw feed mechanism 15. Material deposited on the hearth 2 is carried by the rotation of rabbles 16 attached to rabble shaft 17 across the hearth 2 to be dropped to the hearth 55

4 by means of drop tubes 18 extending through combustion chamber 3. In similar manner the material is carried across hearth 4 and dropped to hearth 6 by means of drop tubes 18 extending 5 through combustion chamber 5, from which it passes through openings 19 to hearth 7. The material delivered to hearth 7 is carried by the rabbles 16 across the hearth 7 to be delivered through chutes 20 to hearth 8, from which it passes generally downwardly successively across the hearths 9, 10, 11, 12, 13, and 14, from the last of which it is discharged through outlet 21 to conventional collection means. Air for combustion in the hearths 8, 9, 10, 11, 12, 13, and 14 also enters 10 through the outlet 21. Gas outlet connections 22 leading to a condenser or stack (not shown) are provided at the top of the furnace for vapors from the absorbent undergoing treatment.

Combustion chambers 3 and 5 provided with 20 openings 23 and 24, respectively, for burners (not shown) are interposed between distillation hearths 2 and 4 and distillation hearths 4 and 6, respectively. Gases formed in combustion chambers 3 and 5 escape through flues 25 and 26, respectively, and are not permitted to come in contact with material undergoing treatment in the distillation zones. Inserts 21, for example, of material of high thermal conductivity are preferably placed in the floor and roof of the combustion chambers in order to facilitate the transfer of heat from the combustion chambers to the absorbent moving across the surfaces of the distillation hearths. These inserts may consist of carborundum, chrome alloy, chrome or cast iron, for 30 example. The main body of the floor and roof may be made from firebrick or other suitable material.

Drop tubes 18, which are shown in the drawings as connecting alternate distillation hearths, may 40 be made of metallic or ceramic material. Steel chrome alloys, steel nickel alloys, cast iron chrome alloys, carborundum or chrome may be used. By the provision of these drop tubes connecting successive distillation zones, the absorbent is subjected 45 to burning or roasting without coming into contact with the heating medium. This feature of the improved apparatus of my invention enables the burning operation to be carried out with indirect heating of the absorbent, thereby eliminating the difficulties due to uncontrolled combustion 50 commonly present when the absorbent is heated by direct contact with the heating medium, in a particularly advantageous manner. Drop tubes 18 are advantageously arranged to be easily 55 removable. The construction of these tubes is shown in detail in Figs. 3 and 4 of the drawings.

As shown in Fig. 3, drop tube 18 is mounted about a tube 28 fixed in the opening in the floor of the combustion chamber. Drop tube 18 is provided at its top with a collar or edge 29 resting upon a ledge in the opening in the roof of the combustion chamber. The drop tube is secured in position by the use of fire clay, for example, which also serves as a seal, preventing the escape 60 of combustion gases to the distillation hearths. In the modification illustrated in Fig. 4, the drop tube is shown as consisting of an upper portion 18a and a lower portion 18b, provided with interlocking edges 30 and 31, respectively, set in a sand seal, for example. The lower portion of the drop tube is shown mounted about a collar 32 set in fire clay or other suitable material while the upper portion is shown as provided with a rim 33 65 engaging the ledge 34 in the roof of the combustion chamber and secured in position by means of 70

fire clay, for example. In the construction shown in either Fig. 3 or 4, the drop tube may be readily removed by breaking the fire clay seal and lifting the tube until it is clear of the openings through which it extends.

In carrying out a burning operation for the revivification of oil saturated fuller's earth, for example, the mineral absorbent is supplied to the uppermost hearth 2 by means of a screw feed mechanism 15 and subjected to indirect 10 heating by heat from the combustion chamber 3 in its passage over the hearth 2. From hearth 2 the absorbent passes by drop tubes 18, extending through combustion chamber 3 to hearth 4, from whence it is carried by the rabbles 16, in a 15 generally downward direction, through the furnace passing successively across the hearths 6, 7, 8, 9, 10, 11, 12, 13, and 14, from the last of which it is discharged through outlet 21 to collection means. Vapors evolved from the absorbent undergoing treatment in distillation hearths 6 and 7 pass through drop tubes 18 to hearth 4 and from hearth 4 through drop tubes 18 to hearth 2 from which they escape through gas outlet connections 22 to a condenser or stack 25 (not shown). An opening 35 is shown provided in hearth 9 for burners (not shown) to complete the burning of the absorbent. Burners may, however, be located on one or more of the hearths in the lower section of the furnace, depending 30 on the amount of heating necessary to complete the burning operation. Combustion gases and vapors driven off from the absorbent in the lower or oxidizing part of the furnace escape through stack opening 36 and are not permitted to come 35 in contact with material in the upper section of the furnace. Ports or openings 37 provide passages for the escape of gases to the stack opening 36. Pyrometer means, such as those shown at 38, may be provided for indicating the temperature 40 to which the absorbent is heated.

As previously noted the apparatus of my invention is in effect divided into two parts, an upper part in which separation of absorbed oil by vaporization from the absorbent, without 45 combustion of such oil is effected, and a lower part in which the burning of the absorbent is completed in much the usual manner. Passage of material through the chutes 20 to maintain 50 a seal to prevent passage of gases from the lower part of the furnace to the upper part of the furnace may be controlled in any conventional manner. In the apparatus illustrated in Fig. 1 counterpoised closure means 40 adapted to maintain a predetermined weight of material in the 55 chutes 20 are shown.

The apparatus of my invention enables the burning operation to be carried out under highly advantageous conditions. By the provision of distillation hearths heated indirectly by combustion chambers having tubes sealed with respect to the combustion chambers extending therethrough, the absorbent is burned out of contact with the heating medium both in its passage over the distillation hearths and in the passage 65 through the tubes and the separation of absorbed oil is effected in the upper part of the furnace by vaporization from the absorbent without combustion of the oil and difficulties due to uncontrolled combustion are avoided. Further, the separation of oil in the upper part of the furnace avoids irregularities or uncontrolled combustion on the hearths in the lower part of the furnace to which the material from which oil has been separated by vaporization on the hearths 2, 4, 6, and 7 is 70 75

supplied through the chutes 20. On the hearth 9, and the hearths below it, the heat necessary to complete burning of the mineral absorbent is supplied by combustion of fuel from burners 5 (not shown), inserted through aperture 35. The supply of fuel from these burners, being independent of the rate of supply of the absorbent to these hearths is readily susceptible to control.

The temperature to be employed in the burning operation will vary depending on the particular material being treated. In burning operations for the recovery of oil saturated clays, fuller's earth, for example, the absorbent may be heated to temperatures from 700° F. to 1250° F., 10 in the hearths in the upper part of the furnace. Heat necessary to complete burning of the absorbent is supplied to the absorbent in the hearths in the lower part of the furnace. Generally higher temperatures may prevail in the 15 lower part of the furnace than those employed in the upper part.

As applied to the burning of oil saturated mineral absorbents, the apparatus of my invention assists in developing improved efficiencies 25 and economies. Unusually high recoveries of the absorbent are possible with the use of my invention and the recovered absorbent usually shows improved absorption efficiency. In some cases, the absorptive efficiencies of the absorbent 30 are actually bettered as compared to fresh, unused absorbent, when recovered in the apparatus of my invention. The useful life of the absorbent may also be prolonged when recovery is

effected in the apparatus of my invention. Recovered in the apparatus of my invention, the absorbent may be reused as many as twenty times, or more, for example, before its efficiency as an absorbent falls to a point making repeated 5 use uneconomical.

I claim:

In a multiple hearth furnace, comprising a series of superimposed hearths and a corresponding series of rabble arms driven from a common 10 vertical shaft for moving solids over the several hearths and generally downwardly through the furnace, the improvement which comprises means for isolating the atmosphere over hearths in the upper part of the furnace from that over hearths 15 in the lower part, combustion chambers arranged beneath the hearths in said upper part with means for isolating the atmosphere in said combustion chambers from that over the hearths in 20 said upper part and with means for indirectly 25 transferring heat from said combustion chambers to such solids moving over the hearths in said upper part, and removable tubes closed with respect to said combustion chambers and extending through each of said combustion chambers 30 for conveying solids downwardly respectively from hearth to hearth in said upper part through said combustion chambers out of contact with the atmosphere therein, said tubes extending from the floor of one hearth to the roof of a lower 35 hearth and being removable through the floor of the hearth from which they extend.

GEORGE R. LEWERS.
